(57) **CLAIM**

The ornamental design for a teakettle, as shown and described.

DESCRIPTION

FIG. 1 is a perspective view of a first embodiment of a teakettle showing my new design;

FIG. 2 is a right side elevational view of the first embodiment of the teakettle, with the left side elevational view being a mirror image thereof;

FIG. 3 is a front elevational view of the first embodiment of the teakettle;

FIG. 4 is a rear elevational view of the first embodiment of the teakettle;

FIG. 5 is a top plan view of the first embodiment of the teakettle;

FIG. 6 is a bottom plan view of the first embodiment of the teakettle;

FIG. 7 is a perspective view of a second embodiment of the teakettle;

FIG. 8 is a right side elevational view of the second embodiment of the teakettle, with the left side elevational view being a mirror image thereof;

FIG. 9 is a front elevational view of the second embodiment of the teakettle;

FIG. 10 is a rear elevational view of the second embodiment of the teakettle;

FIG. 11 is a top plan view of the second embodiment of the teakettle; and,

FIG. 12 is a bottom plan view of the second embodiment of the teakettle.
